(57) **CLAIM**

The ornamental design for an antenna housing, as shown and described.

DESCRIPTION

1. Antenna housing

FIG. 1.1 is a first perspective view of an antenna housing according to our new design;

FIG. 1.2 is a second perspective view thereof;

FIG. 1.3 is a third perspective view thereof;

FIG. 1.4 is a front elevation view thereof;

FIG. 1.5 is a left side view thereof;

FIG. 1.6 is a top plan view thereof;

FIG. 1.7 is a bottom plan view thereof;

FIG. 1.8 is a right side view thereof; and,

FIG. 1.9 is a rear view thereof.

The broken lines show unclaimed environmental structure and form no part of the claimed design.
